FIG. 1 is a front elevational view of the mobile AM/FM cassette recorder/player with CD player of the present invention;
FIG. 2 is a rear elevational view of the mobile AM/FM cassette recorder/player with CD player of FIG. 1;
FIG. 3 is a left side elevational view of the mobile AM/FM cassette recorder/player with CD player of FIG. 1;
FIG. 4 is a right side elevational view of the mobile AM/FM cassette recorder/player with CD player of FIG. 1;
FIG. 5 is a top plan view of the mobile AM/FM cassette recorder/player with CD player of FIG. 1; and,
FIG. 6 is a bottom plan view of the mobile AM/FM cassette recorder/player with CD player of FIG. 1.
